(57) **CLAIM**

The ornamental design for a handheld video boroscope, as
shown and described.

DESCRIPTION

FIG. 1 is an isometric view of a handheld video boroscope
having a housing with a faceplate;

FIG. 2 is a front view of the handheld video boroscope of
FIG. 1;

FIG. 3 is a back view of the handheld video boroscope of
FIG. 1;

FIG. 4 is a right view of the handheld video boroscope of
FIG. 1;

FIG. 5 is a left view of the handheld video boroscope of FIG.
1;

FIG. 6 is a top view of the handheld video boroscope of FIG.
1; and,

FIG. 7 is a bottom view of the handheld video boroscope of
FIG. 1.

The broken lines shown in the drawings represent portions
of the handheld video boroscope that form no part of the
claimed design.
